UNITED STATES PATENT OFFICE

156,807

TIRE PRESSURE GAUGE

Denis James Battersby, West Wittering, England

Application August 18, 1948, Serial No. 148,178
In Great Britain February 19, 1948

Term of patent 14 years

(Cl. D52—1)

To all whom it may concern:

Be it known that I, Denis James Battersby, a British subject, residing at Tylers, Berry Barn Lane, West Wittering, in the county of Sussex, England, have invented a new, original, and ornamental Design for a Tire Pressure Gauge, of which the following is a specification, reference being had to the accompanying drawing, forming part thereof.

Fig. 1 is a face elevational view of a tire pressure gauge showing my new design.

Fig. 2 is a side elevational view.

Fig. 3 is an elevational view opposite to that shown in Fig. 1.

Fig. 4 is a perspective view.

Figs. 5 and 6 are left end and right end views respectively.

I claim:

The ornamental design for a tire pressure gauge, as shown.

D. J. BATTERSBY.
